UNITED STATES PATENT OFFICE

JOHN J. KENNEY, OF PITTSBURGH, PENNSYLVANIA

THERMOSTAT

Application filed December 12, 1928. Serial No. 325,421.

The present invention relates broadly to the art of temperature responsive devices, and more particularly to a thermostatically operated valve. The utility of the present invention however is not limited to the combination of a thermostat and valve, the invention being adaptable to the thermostatic actuation of a wide variety of different controlling means such as valves, switches and 10 the like. Such controlling means are hereinafter referred to in the specification and claims in generic terms.

It is customary in the art to which the present invention relates to provide thermostatically operated structures, such as valves, with the member to be actuated either in alinement or offset from the axis of the heat responsive mechanism by which the actuation is effected. It is also customary to provide adjusting means whereby the temperature range through which the device is operative may be varied at will.

The present invention has for one of its objects the provision of an improved adjusting means which is not only capable of easy adjustment, but which enables an adjustment of almost micrometric characteristics to be obtained.

In the accompanying drawings I have 30 shown for purpose of illustration only, certain preferred embodiments of the present invention.

In the drawings, Figure 1 is a longitudinal sectional view through one form of thermostatic device constructed in accordance with 35 the present invention, and

Figure 2 is a partial sectional view, similar to Figure 1, but illustrating a slightly modified embodiment of the present invention.

In carrying out the present invention there may be provided a thermostatic mechanism including a supporting body 2, herein illustrated as comprising a valve casing, in cooperative relation to a heat responsive actuating means 3.

In the specific embodiment of the invention illustrated in Figure 1, the heat responsive means comprises a relatively expansible and contractile casing 4 with a relatively

non-expansible and non-contractile rod 5 carried thereby. The casing 4 is conveniently closed at one end to provide an abutment for one end of the rod 5, and is enlarged at its opposite end to provide a threaded portion 6 adapted to be threaded into position in a container or other body. Adjacent the threaded portion is formed a chamber 7 within which is positioned an extensible unit 8 in the form of a flexible casing 60 adapted to contain a body of liquid. The liquid utilized will preferably be chosen with respect to its ability to retain a substantially constant volume under temperature changes.

The unit 8 may conveniently comprise a substantially cylindrical corrugated or bellows shaped casing, the ends of which are secured respectively to a disk 9 and a cap 10 in such manner as to provide fluid tight joints therewith. The disk 9 may abut directly against the rod 5 while the cap 10 may be in engagement with the stem 11 of a valve 12 within the supporting body 2.

Threaded through one of the side walls of the cap 10 is a screw 13 provided on its outer end with a thumb screw or adjusting wheel 14 by means of which it may be turned to cause it to project a greater or lesser extent into the interior of the unit 8. When the screw is turned in such direction as to cause 80 it to project into the unit, it will be apparent that the space for the liquid is decreased, thereby causing the unit to expand and decreasing the lost motion between the rod 5 and the valve stem 11. As the screw is 85 turned in the opposite direction, however, a greater space is available for the liquid, thereby permitting the unit 8 to contract and provide a greater lost motion between the parts referred to. Under the condition first

referred to, a relatively smaller change in the temperature of the thermostat will be effective for unseating the valve 12, while under the condition last mentioned it will be necessary to subject the thermostat to a 90 higher temperature in order to effect such an operation. It becomes apparent therefore that by means of the screw 13 it is possible to accurately control the exact temperature at which the device becomes effective for un-

seating the valve or effecting actuation of some other movable member which it is desired to control. By providing the thumb screw or hand wheel 14 with suitable graduations or calibrations adapted to cooperate with an index, pointer or the like, (not shown), it is possible to effect an extremely close adjustment in one direction or the other.

10 In Figure 2 there is illustrated a slightly modified embodiment of the invention in which parts corresponding to the parts already described are designated by the same reference characters having a prime affixed thereto.

15 In this form of the invention the supporting body 2' has spaced arms 15 projecting therefrom, which arms at their extremity carry a cylinder 7'. Extending into the cylinder 7' at one end is the stem 11' of the member to be actuated, while cooperating with the cylinder at its opposite end is a piston 16 secured to the rod 5' and having a tight fit within the cylinder. Extending through 20 the cylinder wall is an adjusting screw 13' operative in the manner referred to in connection with the screw 13 for varying the available room for the liquid. With this construction, movement of the rod 5' is directly effective through the liquid within the 25 cylinder for moving the stem 11', as will be clearly apparent.

30 Instead of utilizing a liquid as hereinafter described, I may utilize a medium having flow characteristics, such, for example, as extremely small shot or the like. In such cases the metal comprising the shot will 35 preferably be selected so as to have an extremely small coefficient of expansion, and thereby a substantially constant volume irrespective of variations in the temperature to which it is subjected. An adjusting screw, 40 similar to those already described, may be utilized for displacing such shot and producing results comparable to those which 45 are produced where a true liquid is utilized.

50 It will also be apparent to those skilled in the art that I may suitably heat insulate the particular portion of the device in which the fluid or medium having flow characteristics 55 is contained, to thereby shield it to as great an extent as possible from any heating influences.

55 Certain advantages of the present invention arise from the provision of a heat responsive mechanism in which a member to be moved is actuated by a heat responsive mechanism through the medium of means having flow characteristics.

60 Other advantages of the invention arise from the provision of the structure of the character referred to in which the medium having flow characteristics may be easily and accurately subjected to an adjusting influence in such manner that the temperature

conditions under which the movable member is actuated may be accurately controlled.

While I have herein illustrated and described certain preferred embodiments of the present invention it will be understood that changes in the construction and operation of the parts may be made without departing either from the spirit of my invention or the scope thereof as defined in my broader claims.

I claim:

1. A thermostat, comprising a supporting body, a member movably carried thereby, a solid heat responsive device for actuating said member, and means of substantially constant over-all dimensions having flow characteristics for transmitting operating pressure from said solid device to said member.

2. A thermostat, comprising a supporting body, a member movably carried thereby, a solid heat responsive device for actuating said member, and a medium having flow characteristics but confined against flow and interposed between said solid device and said member for transmitting pressure from the device to said member.

3. A thermostat, comprising a supporting body, a member movably carried thereby, a heat responsive device for actuating said member, means of substantially constant volume having flow characteristics for transmitting operating pressure from said device to said member, and means for varying the effective volume of said first mentioned means.

4. A thermostat, comprising a supporting body, a member movably carried thereby, a heat responsive device for actuating said member, and a fluid containing chamber of substantially constant over-all length intermediate said device and said member for transmitting pressure from said device to said member, the fluid in said chamber being such as to retain a substantially constant volume under temperature changes.

5. A thermostat, comprising a supporting body, a member movably carried thereby, a heat responsive device for actuating said member, and a fluid containing chamber intermediate said device and said member for transmitting pressure from said device to said member, there being means for changing the effective volume of said chamber, the fluid in said chamber being such as to retain a substantially constant volume under temperature changes.

6. In a thermostat, a supporting body, a member movably carried thereby, a heat responsive device secured in cooperative relation to said member but spaced therefrom, an actuating medium having a substantially negligible coefficient of expansion and having flow characteristics located intermediate said device and said member, and means confining said medium against flow.

7. In a thermostat, a supporting body, a member movably carried thereby, a heat responsive device secured in cooperative relation to said member but spaced therefrom,
5 and an actuating medium having flow characteristics intermediate said device and said member, there being means for varying the effective volume of said medium at will, the fluid in said chamber being such as to retain
10 a substantially constant volume under temperature changes.

In testimony whereof I have hereunto set my hand.

JOHN J. KENNEY.
